(57) **CLAIM**

I claim the ornamental design for a simulator frame, a monitor frame, and a logo plate, as shown and described.

DESCRIPTION

FIG. 1 is a rear perspective view of a simulator frame, monitor frame and logo plate set showing the new design; FIG. 2 is a front perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines in the drawings showing the support structure are directed to environmental subject matter only and form no part of the claimed design.
